DROP TABLE APPARATUS

Louis D. Holmes, Blue Island, and Robert S. Hammon, Winnetka, Ill., assignors to Whiting Corporation, a corporation of Illinois

Application October 7, 1950, Serial No. 189,004

14 Claims. (Cl. 104—32)

1

This application is a continuation-in-part of our co-pending application, Serial No. 138,678, filed January 14, 1950, and refers to drop table apparatus useful in maintaining running gear of railway vehicles.

A drop table installation as utilized in railway shops conventionally includes a pit formed in the shop floor extending transversely across a number of tracks. Rails are laid in the bottom of the pit for a drop table which includes a wheeled frame movable along the rails and lifting beams or members which can be raised and lowered as desired. The pit is spanned by tops which support rails aligned with railway tracks, permitting vehicles to cross the pit when the top is in place. Frequently body support devices are associated with the apparatus for supporting the body of a vehicle from which the trucks or wheels are to be removed. When the trucks have been disconnected, the drop table is moved into position immediately beneath the top upon which the truck is supported, the top released, usually by retracting locking bars, and lowered by the table. To return the trucks upon which maintenance is to be performed to the level of the shop floor, the drop table and top are moved laterally along the pit to the desired location and the lifting members of the drop table again actuated, bringing the top to track level, thus permitting removal of the truck from the top, which is subsequently returned to its previous position.

The track upon which the trucks are moved from the top is known as the release track and is spanned by a release track top. In our previous application we disclosed a release track top having four depending members which could be engaged selectively by the lifting members of the drop table apparatus, thus permitting the release track top to be elevated with the lifting members and allowing the service top to be raised to rail level without employing other apparatus to maneuver the release track top.

In our previously disclosed device, means were not provided for selectively engaging and holding the release track top in either its normal or its elevated position. Furthermore, since the position of the lifting members on the drop table was utilized to control whether or not the lifting members would engage the depending posts of the release track top, a somewhat deeper pit was required than would normally be necessary.

One of the principal objects of this invention is to provide drop table apparatus which will from a single lower position elevate a table top with or without also elevating a release track top at the selection of the operator.

Another object of this invention is to provide drop table apparatus which may be operated in a relatively shallow pit, but which at the same time is capable of elevating a release track top a distance greater than the maximum vertical travel of the lifting beams of the drop table.

A further important object of this invention is

2

to provide means for use with drop table apparatus for engaging or holding upright posts secured to a release track top in one or more predetermined positions.

- 5 Other objects of this invention reside in various novel combinations and sub-combinations of the component elements and which will be more clearly defined in the following detailed description and in the appended drawings, in which:
- 10 Figure 1 is a schematic elevation of a typical drop table installation in a railway shop;
- Figure 2 is a partially broken-away perspective of a drop table installation incorporating our invention;
- 15 Figure 3 is a partial perspective of a lifting post suitable for use in our structure.
- Figure 4 is a partial elevation of a form of our invention employing a release track top permanently secured to lifting posts;
- 20 Figure 5 is a partial detailed elevation of the locking apparatus employed in Figure 2;
- Figure 6 is a partial detailed perspective of a releasable connecting device for coupling a release track top to the lifting posts;
- 25 Figure 7 is a partial detailed perspective view showing a modified form of connection between our lifting posts and the drop table;
- Figure 8 is a partial perspective view of a modified device for connecting the drop table and lifting posts;
- 30 Figure 9 is a partial perspective of the device illustrated in Figure 8 showing the rotatable lug in lowered position;
- Figure 10 is a partial perspective of a modified form of lifting post;
- 35 Figure 11 is a partial perspective of a device suitable for engaging and holding the lifting post illustrated in Figure 10;
- Figure 12 is a partial perspective of a device shown in Figure 11 but incorporating an additional contactor mechanism;
- 40 Figure 13 is a partial perspective of a mechanical device suitable for engaging and holding the lifting post illustrated in Figure 10;
- Figure 14 is a partial perspective view of our invention illustrating a release track in partially lowered position on the drop table; and
- 45 Figure 15 is a partial perspective illustrating the disposition of a typical lifting post in a pit wall.
- 50 Referring to the drawings, we have illustrated in Fig. 1 a typical drop table installation for use in railway maintenance shops having a floor 10 which supports a plurality of tracks 11. A pit 12 extends transversely across the tracks 11 and is provided along its bottom with rails 13 along which a wheeled drop table 14 may be moved. The pit 12 is spanned by one or more service tops 16 and a release track top 17, these tops usually being held in position by retractable bars 18, which may be moved laterally into engagement with the wall of the pit or other suitable support members.

Rails 19 are secured to the upper portion of the tops 16 and 17 for alignment with the corresponding tracks 11. Usually a body support device 21 is associated with one or more of the service tops 16 to support the body of a vehicle when disposed on the top 16 for service, as for example the removal and replacement of trucks. In some instances a tunnel 22 having tracks 23 is provided below floor level as a convenient storage place for trucks, axle assemblies, and the like.

Extending downwardly from the release track top 17 are four corner posts 24, slidably supported in the walls of the pit 12 and engaging the release track top 17 in such manner that upward movement of the posts 24 will elevate the top 17. This is preferably accomplished by connecting the drop table apparatus 14 with the posts 24.

As best shown in Figs. 2 and 3, the posts 24 are preferably structural H-beams having opposed parallel flanges 27 connected by a centrally disposed web 28. To couple the drop table 14 to the posts 24, we provide arm engaging means on each of the posts 24, which as shown in Figure 3 may constitute an opening 29 formed in one of the flanges 27 in a position to receive a retractable lifting arm 31 reciprocally mounted on a lifting beam 32 of the drop table apparatus 14. The opening 29 and the lifting arm 31 are positioned in such manner that the two elements are in registry when the lifting beams 32 of the drop table 14 are in lowered position.

To actuate the lifting arm 31, we provide a crank 33 pivotally secured to the lifting member 32 and pivotally connected to the inner end of the arm 31 by a link 34. An arm 36 is fixed at one end to the crank 33 and pivoted at its opposite end to a piston rod 37, which is in turn secured to a piston disposed in a double acting fluid cylinder 38 also pivotally secured to the lifting member 32, as by a pin 39.

Conduits 41 connect each end of the cylinder 38 with a suitable source of fluid under pressure for reciprocating the piston rods 37, conventional valves being provided in the circuit to permit control of the operation by the drop table operator. Thus, as the piston rod is driven outwardly, the arm 31 will be retracted from engagement with the post 24, the opposite action occurring when the rod 37 is moved inwardly. The exact configuration of the arm 31 is not critical, but should be provided with an upwardly extending lip 42 at its outer extremity to prevent accidental disengagement with the lug means 29.

As indicated in Figures 2 and 6, the release track top 17 may be secured to the posts 24 by retractable arms 18, generally similar to those employed in locking the service track top in position. Lugs 25 may, if desired, be secured to the lifting posts and project outwardly a distance sufficient to engage a notch 26 formed in the projecting portion of the arm 18. Disengagement and subsequent release is obtained when the track top 17 is first elevated raising the top sufficient to disengage the notch 26 from the lug 25 and thereafter retracting the bar 18. It will be understood that the release track top may also be permanently engaged to the posts 24 as indicated in Figure 4. Since retractable arms 18 are conventional for all service track tops 16, these arms may be employed for effecting a connection between the lifting post 24 and the drop table mechanism 14. The service track top 16 is lowered by retracting the locking arms 18 after the top is positioned on the drop table. The service track top 16 is then moved laterally in the pit

by the drop table until the arms 18 are opposite the openings 29 in the post 24 after which they are extended. Upward movement of the lifting beams 32 then therefore raises the release track top 17, which is coupled to the posts 24. The arms 18, applied to either the release track top 17 or the service track top 16 may be actuated by a hydraulic or pneumatic cylinder 30 carried by the respective tops and coupled to the arms through a suitable mechanical linkage, indicated at 35 in Fig. 6.

In some instances the use of the opening illustrated in Fig. 3 is considered objectionable inasmuch as the strength of the post 24 is somewhat reduced, this being particularly true if posts are light in weight or the release track top 17 is unusually heavy. When such circumstances are encountered, a heavy lug 43 (Figure 7) having a notched lower surface 44 may be secured to the post 24, as by welding, and projects inwardly into the pit 12. The notch 44 is engaged by the lip 42 of the arm 31, which also bears against the lower surface of the lug 43. The arm 31 is, of course, retractable to clear the lug 43, thus permitting elevation of the lifting member 32 without raising the posts 24 and the release track top 17.

As an alternative to the retractable lifting arms 18, we may provide a retractable lug, generally designated 46, and illustrated in Figs. 8 and 9.

30 In such instances, a fixed, laterally projecting arm 47 is permanently secured to lifting beam 32 and is disposed in such manner as to engage the lug 46 when the lug is in operative position. Preferably, the lug 46 includes a pair of inwardly extending members 48 welded to each of the posts 24 and spaced apart laterally a distance sufficient to permit upward passage of the arm 47. A plate 49 fits between the members 48 and is secured at its inner end to a bar 51 pivotally mounted 40 in the members 48 in such manner that the plate 49 may be swung from a substantially upright depending position to a substantially horizontal position, in which it engages stops 52 secured to the member 48. The inner end of the bar 51 is 45 provided with an arm 53 movable in a plane parallel to that of the members 48. A shaft 54 extends along the pit wall and is provided at its ends with arms 56, which upon rotation of the shaft 54 engage the under surface of the 50 arms 53, thereby moving the plate member 49 upwardly into position against the stops 52. Movement of the shaft 54 in a reverse direction permits the plate member 49 to fall by gravity to a retracted position. To actuate the shaft 54 55 we provide a lever 57 secured at one end to the shaft 54 and pivoted at its other end to a fluid cylinder 58, solenoid, or the like, the latter being in turn pivotally secured to a member 59 on the pit wall.

60 Thus, when the release track top 17 is to be raised, the cylinder 58 is actuated, moving the plate or lug 49 to horizontal position in the path of the arm 47. If the lug 49 remains lowered, however, the arm 47 will pass upwardly between the members 48 without engaging the plate 49.

In certain instances it may be necessary to elevate the release track top 17 a distance greater than the maximum vertical travel of the lifting beam 32. This may be accomplished by forming on each of the posts 24 a pair of vertically spaced lug means 61. Openings 62 are formed in the web 28 of the beam 24 in predetermined locations and are utilized to lock the posts 24 in position. By utilizing this type of post, the retractable arms 18 on the drop table may be

engaged with the upper of the lugs 61 when it is desired to elevate the release track top 17. Upward movement of the members 32 lifts the post 24 until locking devices engage one of the openings 62 on each of the posts. The table may be then lowered, moved laterally, and again lowered to its lowest position, whereupon the lower of the lugs 61 may be engaged by the arms 31 on the beams 32. Thereafter the locking device extending through the openings 62 may be released and the table top 17 again elevated, whereupon the locking device engages the other of the openings 62 and maintains the release track top in elevated position above floor level. The lugs 61 may be retractable if desired and similar in form to the lug shown in Figs. 8 and 9.

The devices for holding the posts 24 in a predetermined position may be actuated either electrically with devices such as illustrated in Figs. 11 and 12, or by fluid pressure devices, such as illustrated in Fig. 13. In Fig. 11 we have illustrated solenoid 63 having a plunger 64 and secured to the wall of the pit 12 in such position as to permit the plunger 64 to project through the openings 62. Preferably, the plunger 64 is urged outwardly by a spring (not shown), and is withdrawn by actuation of the solenoid. The device shown in Fig. 12 is substantially similar to that shown in Fig. 11 and includes a solenoid 63 and a plunger 64. In this form, however, a contact element 66 is secured to the pit wall and positioned for engagement by the plunger 64 when the latter is extended, thereby completing a contact which may be utilized to indicate to the operator that all locks are engaged; or if desired, utilized to control relays which will prevent actuation of the lifting motors on the drop table 14.

The device illustrated in Fig. 13 incorporates a retractable arm 67 reciprocably supported on the pit wall, which when extended will pass through the openings 62 in the web 28 of the post 24, locking the post in position. The inner end of the arm 67 is connected by a link 68 to a fluid cylinder 69, which is operable to reciprocate the link 68 and arm 67. A lever 71 is pivoted on the pit wall and at its opposite ends to the link 68 and another link 72, which connects with an arm similar to the arm 67, but disposed for engagement with the second of the posts 24 on the same pit wall in such manner that actuation of the cylinder will extend or retract the locking arms simultaneously.

From the foregoing, it may be seen that we have provided apparatus which fulfills the objectives of our invention fully and efficiently. It is furthermore obvious that various of the component parts may be varied without departing from the true spirit and scope of our invention. We therefore do not limit ourselves to the exact details of this disclosure, except as defined in the appended claims.

We claim:

1. In an apparatus for servicing running gear of railway vehicles and the like of the type utilizing a drop table movable along the bottom of a pit extending transversely across railway tracks and spanned by tops including a release track top supported on four depending posts reciprocably mounted in the pit wall, said drop table having vertically movable lifting beams for raising and lowering the tops, the improvement which comprises means for connecting the lifting beams and the posts, said means comprising arm means carried by the lifting beams and an arm engaging means on an adjacent post disposed

for registry with the arm when the lifting beam is in its lowered position, one of said last mentioned means being retractable for selectively preventing lifting engagement of the arm member and the lug member.

2. In an apparatus for servicing running gear of railway vehicles and the like of the type utilizing a drop table movable along the bottom of a pit extending transversely across railway tracks and spanned by tops including a release track top supported on four depending posts reciprocably mounted in the pit wall, said drop table having vertically movable lifting beams for raising and lowering the tops, the improvement which comprises means for connecting the lifting beams and the posts, said means comprising a plurality of lifting arms carried by the lifting beams and supported for sliding movement in a generally horizontal plane for projecting the ends of the arms laterally beyond the beams into engagement with said posts, whereby upward movement of the lifting beams elevates the posts and release track top.

3. In an apparatus for servicing running gear of railway vehicles and the like of the type utilizing a drop table movable along the bottom of a pit extending transversely across railway tracks and spanned by tops including a release track top supported on four depending posts reciprocably mounted in the pit wall, said drop table having vertically movable lifting beams for raising and lowering the tops, the improvement which comprises means for connecting the lifting beams and the posts, said means comprising a plurality of lifting arms carried by the lifting beams and supported for sliding movement in a generally horizontal plane for projecting the ends of the arms laterally beyond said beams, and cooperating means on each of the posts disposed for lifting engagement with the arms when the arms are extended while the lifting beams are in lowered position.

4. In an apparatus for servicing running gear of railway vehicles and the like of the type utilizing a drop table movable along the bottom of a pit extending transversely across railway tracks and spanned by tops including a release track top supported on four depending posts reciprocably mounted in the pit wall, said drop table having vertically movable lifting beams for raising and lowering the tops, the improvement which comprises lug means on each of the posts, arms carried by the lifting beams for lifting engagement with the lug means, a lock for holding the posts in an elevated position, and means for retracting the lock for permitting movement of the posts.

5. In an apparatus for servicing running gear of railway vehicles and the like of the type utilizing a drop table movable along the bottom of a pit extending transversely across railway tracks and spanned by tops including a release track top supported on four depending posts reciprocably mounted in the pit wall, said drop table having vertically movable lifting beams for raising and lowering the tops, the improvement which comprises arm engaging means on each of the posts, arms carried by the lifting beams for lifting engagement with said means, a lock for holding the posts in an elevated position including a retractable arm fixed against vertical movement and adapted for extension through a lateral opening in a post, and means for retracting the arm.

6. In an apparatus for servicing running gear

of railway vehicles and the like of the type utilizing a drop table movable along the bottom of a pit extending transversely across railway tracks and spanned by tops including a release track top supported on four depending posts reciprocably mounted in the pit wall, said drop table having vertically movable lifting beams for raising and lowering the tops, the improvement which comprises arm engaging means on each of the posts, arms carried by the lifting beams for lifting engagement with the arm engaging means, a retractable arm on the pit wall for engagement with an opening in one of the posts when said arm is extended, and a solenoid for retracting the arm.

7. In an apparatus for servicing running gear of railway vehicles and the like of the type utilizing a drop table movable along the bottom of a pit extending transversely across railway tracks and spanned by tops including a release track top supported on four depending posts reciprocably mounted in the pit wall, said drop table having vertically movable lifting beams for raising and lowering the tops, the improvement which comprises lug means on each of the posts, arms carried by the lifting means for lifting engagement with the lug beams, a retractable arm on the pit wall for engagement with an opening in one of the posts when said arm is extended, and a fluid cylinder for retracting the arm. 20

8. In an apparatus for servicing running gear of railway vehicles and the like of the type utilizing a drop table movable along the bottom of a pit extending transversely across railway tracks and spanned by tops including a release track top supported on four depending posts reciprocably mounted in the pit wall, said drop table having vertically movable lifting beams for raising and lowering the tops, the improvement which includes a plurality of laterally extendable arms reciprocally secured on the lifting beams, means for reciprocating the arms, and arm engaging means on each of the posts for lifting engagement with the arms when the beams are in lowered position and the said arms are extended.

9. In an apparatus for servicing running gear of railway vehicles and the like of the type utilizing a drop table movable along the bottom of a pit extending transversely across railway tracks and spanned by tops including a release track top supported on four depending posts reciprocably mounted in the pit wall, said drop table having vertically movable lifting beams for raising and lowering the tops, the improvement which includes a plurality of laterally extendable arms reciprocally secured on the lifting beams, means for reciprocating the arms, and engaging means on each of the posts for lifting engagement with the arms when the beams are in lowered position and the said arms are extended, said engaging means including openings cut in the posts.

10. In an apparatus for servicing running gear of railway vehicles and the like of the type utilizing a drop table movable along the bottom of a pit extending transversely across railway tracks and spanned by tops including a release track top supported on four depending posts reciprocably mounted in the pit wall, said drop table having vertically movable lifting beams for raising and lowering the tops, the improvement which includes a plurality of laterally extendable arms reciprocally secured on the lifting beams, means for reciprocating the arms, engaging means on each of the posts for lifting engagement with the arms when the beams are in lowered position and 75 the arms are extended, said engaging means including openings cut in the posts.

the said arms are extended, said engaging means including openings cut in the posts, and locking means fixed on the pit wall for holding the posts in an elevated position.

5 11. In an apparatus for servicing running gear of railway vehicles and the like of the type utilizing a drop table movable along the bottom of a pit extending transversely across railway tracks and spanned by tops including a release track top supported on four depending posts reciprocably mounted in the pit wall, said drop table having vertically movable lifting beams for raising and lowering the tops, the improvement which comprises a plurality of fixed rigid lifting arms carried

10 by the lifting beams and projecting laterally towards the posts and a retractable lug on each of the posts, each of said lugs including a member movable into and out of the path of the corresponding lifting arm.

15 12. In an apparatus for servicing running gear of railway vehicles and the like of the type utilizing a drop table movable along the bottom of a pit extending transversely across railway tracks and spanned by tops including a release track top supported on four depending posts reciprocably mounted in the pit wall, said drop table having vertically movable lifting beams for raising and lowering the tops, the improvement which comprises a plurality of fixed rigid lifting arms carried by the lifting beams and projecting laterally towards the posts, a retractable lug on each of the posts, each of said lugs including a member movable into and out of the path of the corresponding lifting arm, and power means for actuating said lugs.

30 13. In an apparatus for servicing running gear of railway vehicles and the like of the type utilizing a drop table movable along the bottom of a pit extending transversely across railway tracks and spanned by tops including a release track top supported on four depending posts reciprocably mounted in the pit wall, said drop table having vertically movable lifting beams for raising and lowering the tops, the improvement which comprises a plurality of fixed rigid lifting arms carried by the lifting beams and projecting laterally towards the posts, a retractable lug on each of the posts, each of said lugs including a member movable into and out of the path of the corresponding lifting arm, and power means for actuating said lugs.

35 14. In an apparatus for servicing running gear of railway vehicles and the like of the type utilizing a drop table movable along the bottom of a pit extending transversely across railway tracks and spanned by tops including a release track top supported on four depending posts reciprocably mounted in the pit wall, said drop table having vertically movable lifting beams for raising and lowering the tops, the improvement which comprises a plurality of fixed rigid lifting arms carried by the lifting beams and projecting laterally towards the posts, a retractable lug on each of the posts, each of said lugs including a member movable into and out of the path of the corresponding lifting arm, and means for locking each of the posts in an elevated position.

40 15. In an apparatus for servicing running gear of railway vehicles and the like of the type utilizing a drop table movable along the bottom of a pit extending transversely across railway tracks and spanned by tops including a release track top supported on four depending posts reciprocably mounted in the pit wall, said drop table having vertically movable lifting beams for raising and lowering the tops, the improvement which comprises a pair of vertically spaced lug means on each of the posts, laterally extending arms reciprocally carried by the lifting beams for lifting engagement with said lugs when extended, and means for locking the posts in an elevated position.
